By

UNITED STATES PATENT OFFICE.

AUGUST T. WEHRLE, OF NEWARK, OHIO.

DESIGN FOR A GAS-RANGE.

No. 38,574.

Specification for Design.

Patented May 14, 1907.

Application filed March 12, 1907. Serial No. 362,076. Term of patent 7 years.

To all whom it may concern:

Be it known that I, AUGUST T. WEHRLE, a citizen of the United States, residing at Newark, county of Licking, Ohio, have invented a certain new, original, and ornamental Design for a Gas-Range, of which the following is a specification, reference being had to the accompanying drawing, forming part thereof.

My invention is illustrated by the accompanying drawings, in which the gas range is

shown by a single figure, in front perspective, disclosing the design of my invention.

I claim;

The ornamental design for a gas range, substantially as shown.

AUGUST T. WEHRLE.
